UNITED STATES PATENT OFFICE.

ABRAHAM PERLMAN, OF NEW YORK, N. Y., ASSIGNOR TO STAR BALL BEARING DOOR-HANGER COMPANY, OF NEW YORK, N. Y., A CORPORATION OF NEW YORK.

DOOR-HANGER.

1,083,295.

Specification of Letters Patent.

Patented Jan. 6, 1914.

Application filed June 6, 1912. Serial No. 702,085.

To all whom it may concern:

Be it known that I, ABRAHAM PERLMAN, a citizen of the United States, and resident of the city of New York, in the county of 5 New York and State of New York, have invented certain new and useful Improvements in Door-Hangers, of which the following is a specification.

This invention relates to improvements in 10 door hangers and more especially to anti-frictional sliding doors.

The primary object of the invention is to 15 provide a hanger to be employed for supporting any number of sliding doors which it may be desired to employ in a set for closing an opening adapted to be mounted upon roller bearings and in such a manner that each door of the set is capable of a sliding motion at one-half of the speed of the door 20 which precedes it.

With these general objects in view and others that will appear as the nature of the invention is better understood, the same consists in the novel combination and arrangement of parts hereinafter fully described, 25 illustrated in the accompanying drawings and pointed out in the appended claims.

In the drawings forming a part of this application and in which like reference 30 numerals designate corresponding parts throughout the several views: Figure 1 is a plan view of two sliding doors illustrated in closed position and provided with the present invention. Fig. 2 is a side elevation 35 thereof showing the doors in their locked closed positions, Fig. 3 is a detail vertical sectional view taken upon line 3—3, Fig. 2, Fig. 4 is an end elevation of the structure shown in Fig. 2, but partly in vertical section upon the line 4—4 of said figure.

Referring in detail to the drawings, a suitable support 10 such as the side of a building is shown and adjacent which the two sliding doors 11 and 12 are adapted to 45 be slidably hung upon the respective tracks 13 and 14, which are mounted upon the projecting brackets 15 of the support. Each of said tracks 13 and 14 are of identical construction being each formed of two channel

bars 16, which are spaced apart in parallel 50 relations by the end blocks 17 and thus providing a central space the entire length of the tracks for the reception at both the top and bottom of the rails of portions of the traction rollers hereinafter described. 55

The general operation of the hanger and roller bearings will now be described, it being noted that the track 13 is provided longer than track 14 to allow for the closing 60 of the front portion of the opening by the door 11, while the door 12 positioned upon said shorter track is limited in its movement thereon to a position for closing the opening up to the rear end of the forward door 11. 65

Each hanger consists of a yoke frame 18 with a strap 19 spanning the lower portion of the yoke and provided with an inwardly extending perforated boss 20 and to which are secured the bolts 21 upon which the 70 doors hang. Spaced slightly above said strap and boss and upon either side of the latter are two stub axles 22 each having journaled thereon a roller 23 adapted to move in contact with the lower surface of 75 the rails 16 with a central slightly tapered annular flange 24 adapted for movement between the respective rails forming each track.

An inwardly projecting top flange 25 of 80 each hanger has a similar track 26 depending from the underneath surface thereof. Said track 26 is of sufficient length to be mounted upon as many hangers as it is desired to supply to any one door, two being 85 illustrated for each door in the present case, the said track also positioning said hangers a proper distance apart as well as extending a desired distance beyond each hanger for the purpose of giving a bearing surface 90 upon a predetermined number of the supporting rollers employed therewith.

The movable tracks 26 of the hangers are slidably mounted upon the rollers 27, which are connected together in any number 95 and any desired distance apart by the parallel outside strips 28, between which said rollers are journaled. The strips 28

of the rollers of the outer track 13 are rigidly secured to the movable track 26 of the hanger sliding upon the track 14 by the several connecting means 29.

5 The operation of the device will be apparent upon viewing the drawings, in that with the doors in their closed positions shown in Fig. 2, a movement imparted to the door 11 toward the door 12 would result in 10 a sliding of the same with its hanger rollers 23 beneath the track 13 and the upper rollers 27 upon the top of said track 13 with the movable track 26 in turn mounted upon the said rollers. The movement of the door 15 11 in this direction may continue until the stop 30 secured centrally of the track 26 of the hanger of said door 11 contacts the guide pin 31 positioned to engage the same upon the outer roller strip, the same being 20 so positioned that at this point of engagement, the respective upper tracks of the two doors will terminate in the same plane and the doors 11 and 12 will be positioned one exactly over the other. A further movement imparted to door 11 in the same direction would then necessarily also move the outer rollers and the inner track 26 secured thereto of the hangers of the door 12 and thereby imparting movement to this door.

30 In the closing operation the door 11 may be moved toward the left upon the outer rollers 27 until the stop 30 engages the forward stop pin 30' at which time the doors are in closed position. Such movements, it 35 will be apparent, allow the door 11 to move at double the speed at which the door 12 will move, this being due to the fact that a movement of the track 26 of the door 11 not only propels the same upon the outer rollers 27, but also forces said rollers to turn upon their track 13 giving double speed. The relative positions of the stop 30 and the stop pins 30' and 31 is such that when the doors 11 and 12 are in their closed positions, the 40 stop 30 engages the pin 30' while upon the opening movement, the stop 30 travels until engaging the pin 31 and at which time the doors are completely opened, the movement of the door 11 being at double the rate of 45 speed of that of the door 12, the stop pins 30' and 31 therefor limiting the movement of the door 11 by an engagement therewith of the stop 30 in either the extreme open or closed position.

50 In connection with my improved hanger, I have illustrated a latching device carried by the forward yoke 18 and operable by the lever 46 and rod 45 carried by the door 11. This device embodies a latch 33 pivoted to 55 said yoke 18 and having a bottom notch 34 for engagement with the keeper 35 secured to the stationary track 13. A bolt 40 in 60 spanning engagement with the latch 33 rests upon the top of the rod 45, while the expan-

sion spring 43 normally depresses both the 65 bolt 40 and the latch 33, thereby tending to prevent accidental disengagement of the latch from the keeper. The latch is easily manually elevated for releasing the same by an upward movement imparted to the bolt 70 40 through the agency of the rod 45 upon turning down the lever 46.

In this invention the strips 28 may be formed of square tube channel iron and in which event the connecting portion of the 75 bracket 29 between the two tracks is unnecessary. I-beams might also be used as bearing strips for the rollers with the rollers journaled in perforations through the web of the beams. The particular form of the 80 rollers adds materially to the invention, the rollers which are mounted in the strips 28, being the supporting anti-friction members for sustaining the entire weight of the doors.

While the forms of the invention herein-after shown and described are what are believed to be preferable embodiments thereof, it is nevertheless to be understood that minor changes may be made in form, proportion and details of construction without departing from the spirit and scope of the 90 invention, as set forth in the appended claims.

Having thus described the invention, what I claim is:—

1. A device of the class described, comprising two doors, two tracks arranged upon the same horizontal plane, a set of rollers positioned for movement upon each of said tracks, side strips in separate ones of which 100 said rollers are journaled, upper tracks positioned for movement upon each set of rollers, yoke frames carried by said upper tracks and one of said doors suspended from each of said frames, connecting means between the rearward one of said upper tracks and the forward set of connecting strips, stop pins outwardly projecting adjacent the ends of said last named strips and a stop carried by the forwardly positioned one of 110 said upper tracks and adapted for engaging said pins when the doors are completely opened or closed.

2. A device of the class described comprising parallel tracks, a roller carrying 115 frame upon each of said tracks, means for suspending a separate door upon the frame of each track, means for shifting one of said doors upon a movement of the frame for the other door, and means carried by said last 120 named frame adapted for limiting the movement of said other door at its extreme open and closed position.

3. A device of the class described comprising two doors, one of said doors adapted 125 for movement at double the rate of speed of the other, a carrying track for the door of greater speed, a roller carrying frame for

said track, means connecting said frame and the door of less speed adapted for actuating the latter upon a movement of said frame, a stop upon said track and stop pins carried by said frame adapted for engagement by said stop at both the extreme open and closed positions of said doors.

Signed at the city of New York, in the county of New York, and State of New York, this 23d day of May, A. D. 1912.

ABRAHAM PERLMAN.
